CLAIM

The ornamental design for a death care merchandise display unit, as shown and described.

DESCRIPTION

The sole FIGURE is a top, front and side perspective view of a death care merchandise display unit showing our new design.

The broken line showing of the structure inside the cornice and the indicia on the front of the cornice is for illustrative purposes only and form no part of the claimed design.

The surface(s) or portion(s) of the article not shown in the drawing or described in the specification form(s) no part of the claimed design.
